HAND LOOM

Jeremiah A. Pecott, deceased, late of Lawrence,
Mass., by Bertha A. Pecott, administratrix,
Lawrence, Mass.

Application May 16, 1946, Serial No. 670,234

4 Claims. (Cl. 139—33)

1

This invention relates to what might be called hand looms or toy looms as distinguished from power looms.

Its purpose is to provide a loom which can be operated by invalids, disabled soldiers and others who desire to fix their attention on making a certain pattern on certain kinds of cloth such as scarves, ties and belts.

The main feature of the device is the provision of a top driving roller and a bottom driving roller between which are two driven or idle rollers and heddles which are substantially endless each fastened to a driving and passing around a driven roller and each having two eyes whereby these eyes can be arranged in different rows by turning one or both of the driving rollers a greater or less extent and while sheds are so formed, passing a shuttle or shuttles through these sheds to produce different weaves or patterns.

Various patterns can be produced, as for instance where there are two sets of endless heddles, or heddles each of which has at least two eyes by moving one or both in various ways so as to open a shed between certain warp parts, bringing certain other warp parts at the top and others at the bottom.

In the drawings,

Fig. 1 is a diagrammatic side elevation of the device showing heddle eyes and warp members in one of many possible positions.

Fig. 2 is a partly diagrammatic plan view of the device.

Fig. 3 is a diagrammatic side elevation of part of Fig. 1, showing the heddles and heddle eyes in a different position from Fig. 1.

Fig. 4 is a diagrammatic side elevation, similar to Fig. 3, showing the heddles and heddle eyes in still a different position from Figs. 1 and 3.

Fig. 5 is a diagrammatic plan view similar to the left hand side of Fig. 2 with the special type of shuttle turned around and pushed up against the cloth.

Fig. 6 is a transverse sectional view showing one way of attaching the ends of each endless heddle to a heddle driving roller.

Fig. 7 is a detail showing a type of driven roller or bar provided with parallel annular grooves to keep the endless heddles from slipping sideways.

Fig. 8 is a diagrammatic side elevation similar to Fig. 1, showing the heddles and heddle eyes in a different position from Figs. 1, 3 and 4, and showing another type of shuttle.

Fig. 9 is an elevational view of part of a comb

2

type of reed such as shown in Fig. 8, namely a separate reed or comb.

Fig. 10 is a side elevational view of a type of shuttle shown in Fig. 8.

5 In the drawings, there is shown what, for convenience, will be called the top heddles H, H, and what will be called the bottom heddles K, K, and reference will be made to the roller or other member around which they pass as the top heddle 10 driving and driven roller and the bottom heddle driving and driven rollers. These terms will be used because the upper parts of the top heddles are at the top and the bottom parts of the bottom heddles are at the bottom.

15 It is understood that the top heddles and the bottom heddles may alternate or may be grouped in any desired arrangement so as to form any desired pattern.

In the drawings F represents a frame at one 20 end of which is a revoluble warp beam 50. Handle 54 and bearings are at the other end for turning a revoluble cloth beam 51. W is a warp shown as divided into four parts 15, 16, 17, and 18.

25 20 and 21 are uprights extending up on each side of frame F between the warp beam 50 and the cloth beam 51.

A is a top heddle driving roller carried by shaft 1 rotatably mounted between the tops of the uprights 20 and 21 in bearings 31, 31. Shaft 1 carries at one end a turning member or handle 2. 3 is a top heddle driven roller carried by and shown as being mounted between the uprights 20 and 21.

35 H, H are what will be called the top heddles which are really endless heddles as they pass around top heddle driving roller A and top heddle driven roller 3, being fastened to roller A and each having the heddle eyes 5 and 6 shown as 40 evenly spaced from each other.

B is a bottom heddle driving roller its shaft 11 being rotatably mounted in bearings 41, 41 at the bottom part of the uprights 20 and 21, the shaft 11 also carrying a turning member or 45 handle 12.

13 is a bottom heddle driven roller shown as being rotatably mounted between uprights 20 and 21.

K, K, are bottom heddles each of which passes 50 around both bottom rollers B and 13, each being fastened to roller B and being provided with oppositely disposed warp thread eyes 7 and 8.

S is a special type of shuttle which as shown tapers down along one side to a relatively thin 55 edge 60 while on the other edge are the winding

posts 61 and 62 around which filling thread 19 can be wound.

As shown, there is no reed but there are on the frame on each side near the cloth beam stop pins 22 and 23.

The operation is as follows:

With the warp threads 15 passing through eyes 5, 16 passing through eyes 6, 17 passing through 7, and 18 passing through 8, as shown in Fig. 1, a shuttle S is passed between the shed formed by the threads 15 and 16, the winding posts 61 and 62 for filling thread 19 being on the side toward the cloth C. The shuttle and the filling thread 19 are pulled smooth and then either the top driving roller A or the bottom driving roller B or both, are so moved as to change the position of the four eyes 5, 6, 7, and 8, with their respective threads to cross the warp threads and lock filling 19, whereupon the shuttle is pushed back through any shed of the warp with its tapered edge on the cloth side and is pushed towards the cloth until stopped by the pins 22 and 23, this motion slightly unwinding the warp from the warp beam 50. This is shown in Fig. 5.

The cloth beam 51 can be slightly moved from time to time to take up the slack.

The shuttle therefore takes the place of the ordinary reed as well as of the shuttle and the pins 22 and 23 keep the filling right up close and at right angles to the warp.

Herein, it is shown the top driven heddle roller 3 and the bottom driven heddle roller 13 as revolute but it is obvious that smooth bars might be substituted for them as the respective heddles could slip around such bars without damage. It is clear that instead of two eyes equally distanced from each other on each heddle, three or more eyes or two eyes disposed at irregular distances from each other might be used.

52 is a cloth support upon which the cloth rests and which may or may not be used.

Referring to Figs. 1, 3, 4 and 8, different arrangements of the warp parts are shown as follows:

In Fig. 1, the shuttle S passes between the wide shed between parts 16 and 15 while the part 17 at the top is stationary.

In Fig. 3, the shuttle S passes between the warp parts 16 and 15 with part 18 at the top.

In Fig. 4, the shuttle S passes between the warp parts 17 and 18 with part 15 at the top and in Fig. 8, the shuttle T passes between the warp parts 15 and 16 with the part 17 at the top.

As shown in Fig. 6, the ends of any endless heddle such as H can pass through a hole such as 63 and be tied in a knot such as at 64.

As shown in Fig. 7, any one of the so-called driven rollers indicated by 3, whether it is revolute or stationary, can be provided with annular grooves 10 to prevent the heddles from slipping sideways.

As shown in Fig. 8, endless heddles H and K and rollers A and B can be used but instead of a two purpose shuttle such as S, which serves not only to carry the filling but as a beat up device, shuttle T of the usual type can be used and a comb type reed R with teeth 11 can be used to beat up the picked filling thread against the cloth, this comb being stopped by pins 22 and 23 as in the other construction.

What is claimed is:

1. A hand loom having a frame provided with two uprights, a top heddle driving roller rotatably mounted in said uprights and provided with a turning handle; a top heddle driven roller ro-

tatably mounted in said upright below the top driving roller; top heddles passing around both top heddle rollers, each heddle being attached to the top heddle driving roller and having two warp thread eyes; a bottom heddle driving roller rotatably mounted between the uprights, positioned below the top heddle driven roller and including a turning handle; a bottom heddle driven roller rotatably mounted between the uprights and positioned above the top heddle driven roller; bottom heddles passing around both bottom heddle rollers each heddle being attached to the bottom heddle driving roller and having two warp thread eyes; a warp beam positioned on one side of the uprights; and a cloth beam positioned on the other side of the uprights, whereby certain warp threads from the warp beam can pass through certain eyes and other warp threads can pass through other eyes to form various sheds for the passage of a shuttle or shuttles.

2. A hand loom having a frame provided with two uprights, a top heddle driving roller rotatably mounted in said uprights and provided with a turning handle; a top heddle driven roller rotatably mounted in said upright below the top driving roller; endless top heddles passing around both top heddle rollers, each heddle being attached to the top heddle driving roller and having a plurality of warp thread eyes; a bottom heddle driving roller rotatably mounted between the uprights, positioned below the top heddle driven roller and including a turning handle; a bottom heddle driven roller rotatably mounted between the uprights and positioned above the top heddle driven roller; bottom endless heddles passing around both bottom heddle rollers each heddle being attached to the bottom heddle driving roller and having a plurality of warp thread eyes; a warp beam positioned on one side of the uprights; and a cloth beam positioned on the other side of the uprights, whereby certain warp threads from the warp beam can pass through certain eyes and other warp threads can pass through other eyes to form various sheds for the passage of a shuttle or shuttles; together with stop pins between the cloth beam and the uprights to limit the movement of any beating up device.

3. A hand loom having a frame provided with two uprights, a top heddle driving roller rotatably mounted in said uprights and provided with a turning handle; a top heddle driven roller formed with annular grooves rotatably mounted in said upright below the top driving roller; endless top heddles passing around both top heddle rollers, each heddle being attached to the top heddle driving roller and having a plurality of warp thread eyes; a bottom heddle driving roller rotatably mounted between the uprights, positioned below the top heddle driven roller and including a turning handle; a bottom heddle driven roller formed with annular grooves rotatably mounted between the uprights and positioned above the top heddle driven roller; bottom endless heddles passing around both bottom heddle rollers each heddle being attached to the bottom heddle driving roller and having a plurality of warp thread eyes; a warp beam positioned on one side of the uprights; and a cloth beam positioned on the other side of the uprights, whereby certain warp threads from the warp beam can pass through certain eyes and other warp threads can pass through other eyes to form various sheds for the passage of a shuttle or shuttles; together with stop pins between the cloth beam

and the uprights to limit the movement of any beating up device.

4. A hand loom having a frame provided with two uprights, a top heddle driving roller rotatably mounted in said uprights and provided with a turning handle; a top heddle driven roller rotatably mounted in said upright below the top driving roller; endless top heddles passing around both top heddle rollers, each heddle being attached to the top heddle driving roller and having a plurality of warp thread eyes; a bottom heddle driving roller rotatably mounted between the uprights, positioned below the top heddle driven roller and including a turning handle; a bottom heddle driven roller rotatably mounted between the uprights and positioned above the top heddle driven roller; bottom endless heddles passing around both bottom heddle rollers each heddle being attached to the bottom heddle driving roller and having a plurality of warp thread eyes; a warp beam positioned on one side of the uprights; and a cloth beam positioned on the other side of the uprights, whereby certain warp threads from the warp beam can pass through certain eyes and other warp threads can pass

through other eyes to form various sheds for the passage of a shuttle or shuttles; together with stop pins between the cloth beam and the uprights to limit the movement of any beating up device, the front and back parts of each of the endless heddles lying in a single vertical plane, all such planes being substantially parallel whereby all of the heddles are side by side in a single row.

10

5. The front and back parts of each of the endless heddles lying in a single vertical plane, all such planes being substantially parallel whereby all of the heddles are side by side in a single row.
